HOLDER AND KNIFE BLADE HAVING A
TUNGSTEN CARBIDE EDGE

Robert A. Bowes, Chicago, Ill., assignor to Carbide
Saw & Tool Company, Chicago, Ill., a corpora-
tion of Illinois

Application December 23, 1950, Serial No. 202,466

4 Claims. (Cl. 30—317)

1

My invention relates to a knife blade, and more particularly to a knife blade having a tungsten carbide edge. My invention has particular utility in cutting materials such as asphalt roofing or other abrasive compositions, siding and roofing materials. My knife blade is also useful in scribing hard and abrasive materials such as concrete, metals, etc. in layout or similar work.

It is an object of my invention to provide a knife blade having a tungsten carbide edge which is simple in construction and economical to manufacture. It is another object of my invention to provide a carbide-edged knife blade which is useful for difficult cutting and scribing operations such as described above. It is also an object of my invention to design a knife blade structure which is attached to or detached from a holder, and to provide a holder for use therewith. It is a further object of my invention to provide a knife blade or support for a carbide edge which is capable of being formed from one thin piece of metal by operations such as stamping, bending, soldering, etc.

Another object of my invention is to provide a carbide-edged knife blade having a laminated point construction which is adapted to reinforce the point and the rest of the blade projecting outwardly from the handle. It is a still further object of my invention to adapt my blade structure so as to provide a seat for a carbide edge or tip without the necessity for separate grinding or cutting operations to prepare such seat. Also it is an object of my invention to provide a seat structure on my knife blade which will hold the carbide edge or tip firmly against bending, or twisting or other motion which would tend to loosen the carbide tip from the rest of the blade. A still further object of my invention is to provide a knife blade structure in which the reinforced point portion is made to cooperate with the handle so that the blade will be held more securely within the handle. Further objects and advantages will appear as the specification proceeds.

My invention is shown in an illustrative preferred embodiment in the accompanying drawing, in which—

Fig. 1 is a perspective view of one form of my knife blade secured within a suitable holder; Fig. 2, a perspective view of my knife blade showing the folded point reenforcing portion and tungsten carbide edge; Fig. 3, a perspective view similar to Fig. 2 but showing the other side of my knife blade and the beveled edge of the main

2

blade portion; Fig. 4, a sectional view taken in elevation on line 4—4 of Fig. 1 showing the laminated point construction and the tungsten carbide edge secured within the recess; Fig. 5, a view similar to Fig. 4 but showing the reenforced point before the installation of the tungsten carbide edge and before the adjacent edge is beveled; Fig. 6, a view similar to Figs. 4 and 5 showing tungsten carbide edge in place and broken line indicating the line along which the adjacent layer can be beveled; Fig. 7, a plan view of a die cut metal shape which can be readily formed into my knife blade by folding along the indicated dotted line; and Fig. 8, a top cross sectional view taken along line 8—8 of Fig. 1 showing the cooperation between the shoulder provided by the folded point with the forward face of the handle.

As illustrated in the accompanying drawing, 10 20 generally designates my new knife blade. Knife blade 10 in the embodiment shown consists of a flat hook-shaped metallic strip 11, as seen more clearly in Fig. 3. Strip 11 is composed of a holder engaging tongue portion 12 having a 25 notch or recess 13 in the bottom edge thereof. Tongue 12 is integrally formed near its forward end with a laterally-extending pointed portion 14.

Looking primarily at Fig. 2, a thin metallic strip 15 is superposed on pointed portion 14 and the forward part of tongue portion 12. In the 30 illustration given, strip 15 is shaped to correspond to point 14 and the forward portion of tongue 12 and integrally formed with these members by means of fold 16. It will be apparent, however, that strip 15 can also be made 35 separately from hook-shaped strip 11 and then rigidly secured thereto by any suitable means such as brazing, soldering, spot welding, etc. In the illustration given, superposed strip 15 is secured to strip 11 at its uppermost corner by 40 means of solder 17. Since strips 11 and 15 are held together by fold 16, only a small amount of solder is required at 17 to secure these strips into a laminated point which reinforces the entire knife blade 10.

As shown in the drawings, folded overlapping strip 15 is cut back along the rear edge of its laterally-extending point to provide recess 18 for receiving a thin piece or slug of tungsten carbide 19. It will be apparent, however, that the adjacent pointed portion 14 could be cut back to provide a recess which would serve the same purpose as recess 18. A slug of tungsten carbide is molded from a tungsten carbide molding powder according to conventional procedures

for insertion in recess 18. I have found it preferable to mold slug 19 in the exact shape required for insertion in recess 18, and I have found it desirable to slightly taper slug 19 as shown more clearly in Figs. 4 and 6. Slug 19 can be rigidly secured within the seat provided by the cooperation of members 14 and 15 by any suitable means such as brazing or soldering. I have found that a silver-braze is admirably suited to securing slug 19 within recess 18.

It will be noted that superposed strip 15 provides a shoulder 20 extending across tongue 12 at the forward end thereof, as seen more clearly in Figs. 2 and 8. Shoulder 20, as shown in Figs. 1 and 8, can be conveniently made to abut the forward face 21 of a handle or holder 22. In the illustration given, holder 22 is composed of two complementary halves 22a and 22b which are secured together by means of screw 23. Within handle 22 a lug or projection 24 is provided on handle half 22b. The purpose of lug 24 is to engage notch 13 in the bottom edge of tongue 12 and thereby restrain blade 10 against longitudinal movement. With the structure shown, shoulder 20 abuts face 21 of handle 22 and prevents blade 10 from being rotated either upwardly or downwardly within holder 22. Thus, strip 15 not only provides a seat for tungsten carbide edge 19 but also provides a shoulder 20 which cooperates with handle 22 to hold plate 10 securely therein.

Operation

I have found that my knife blade can be conveniently constructed from a thin piece of metal such as cold rolled steel by die cutting a blank of the metal by stamping operation to produce the metallic shape shown in Fig. 7. In this way, the entire blade 10, except for the tungsten carbide edge 19, is formed in one piece and by one stamping operation. This is particularly advantageous since recess 18 is thus formed without need for a separate grinding or cutting operation and strip 15 is made easier to rigidly secure to point 14 and the forward portion of tongue 12.

The die cut shape shown in Fig. 7 is then folded along the dotted line as designated so as to bring strip 15 and strip 11 into close juxtaposition, as shown in Fig. 5. The upper corner of strip 15 is then soldered or secured by other suitable means to tongue 12.

A tungsten carbide slug or edge member 19, preferably slightly tapered, is then secured within recess 18, as shown in Fig. 6. This can be conveniently done by brazing with a silver solder. If desired, the adjacent layer of point 14 can then be ground off along the broken line indicated in Fig. 6 to produce beveled edge 25, as shown in Fig. 4.

Blade 10 is then in completed form and a handle similar to 22 can be attached thereto so that the knife blade can be used in cutting and scribbling operations. By providing the hook-shaped blade, as illustrated, with a carbide tip on the rear edge of the laterally-extending pointed portion, the assembled knife as shown in Fig. 1 can best be used by drawing it toward the holder across the surface to be cut or scribed. It will be noted that this method of using the assembled knife tends to rotate blade 10 upwardly within handle 22. However, this motion is effectively prevented by the engagement of shoulder 20 with face 21, as described above.

By actual use of my knife blade under extreme conditions of wear and abrasion, I have demonstrated that it stands up remarkably well. The

tungsten carbide edge 19 is held securely within recess 18 against movement in all directions, and does not tend to become loosened or disengaged from the laminated point. Also, the laminated point construction of my blade prevents it from being bent or twisted during use even though a relatively thin sheet of cold rolled steel is used to form the blade.

As I have pointed out above, my knife blade is designed for use in cutting difficult materials such as asphalt roofing and siding. It has been found that my knife blade can be used to cut such difficult materials on the job and in inaccessible places such as on scaffolds. Thus, it is possible for a workman to carry out the cutting operation at the point of installation of the material without the need for electric power connections such as would be required for the conventional motor driven cutting tools.

While in the foregoing specification I have set forth one specific structure in considerable detail for the purpose of illustrating one embodiment of my invention, it will be understood that such details of structure may be varied widely by those skilled in the art without departing from the spirit of my invention.

I claim:

1. In combination with a holder having a transverse forward face, said face having a tongue-receiving recess extending inwardly therefrom, a tungsten carbide-edged knife blade comprising a thin metallic sheet providing a holder-engaging tongue portion integrally connected near its forward edge with a pointed portion, said tongue portion being received within said holder recess and being provided with a notch within said recess, said holder providing a projection within said recess engaging the notch in said tongue portion and cooperating therewith to restrain longitudinal movement of said knife blade, a correspondingly shaped metallic strip superimposed upon and integrally connected along one edge thereof with the forwardmost part of said tongue portion and said pointed portion to form a laminated point having two layers, one of said layers having a recess along the edge of said point, and a flat slug of tungsten carbide rigidly secured in said last-mentioned recess to provide a cutting edge, said strip overlying only the forward part of said tongue portion and terminating at its rear in an edge providing a raised shoulder extending across said tongue portion and engaging the transverse forward face of said holder, thereby tending to prevent any rotation of said knife blade when secured within said holder during the use of the assembled knife.

2. A tungsten carbide-edged knife blade, comprising a thin metallic sheet providing a holder-engaging tongue portion integrally formed near its forward end with a pointed portion, a correspondingly shaped metallic strip integrally connected along one edge thereof to the forwardmost part of said tongue portion and overlying the forward tongue portion and said pointed portion, thereby providing a laminated point having at least two layers, one of said layers having a recess along the edge of said point, and a flat slug of tungsten carbide rigidly secured in said recess to provide a cutting edge, said strip terminating at its rear in an edge extending transversely across the intermediate part of said tongue portion and providing a raised shoulder thereacross for engaging a transverse forward face of a holder and thereby preventing rotation of said knife blade when secured within the holder.

3. A tungsten carbide-edged knife blade, comprising a thin metallic sheet providing a holder-engaging tongue portion integrally formed near its forward end with a laterally-extending pointed portion, a correspondingly shaped metallic strip integrally connected along one edge thereof to the forwardmost part of said tongue portion and overlying the forward tongue portion and said pointed portion, thereby providing a laminated point having at least two layers, one of said layers having a recess along the rearward edge of said point, and a flat slug of tungsten carbide rigidly secured in said recess to provide a cutting edge, said strip terminating at its rear in an edge extending transversely across the intermediate part of said tongue portion and providing a raised shoulder thereacross for engaging a transverse forward face of a holder and thereby preventing rotation of said knife blade when secured within the holder.

4. In combination with a holder having a transverse forward face, said face having a tongue-receiving recess extending inwardly therefrom, a tungsten carbide-edged knife blade comprising a thin metallic sheet providing a holder-engaging tongue portion integrally connected near its forward edge with a laterally-extending pointed portion, said tongue portion being received within said holder recess and being provided with a

notch within said recess, said holder providing a projection within said recess engaging the notch in said tongue portion and cooperating therewith to restrain longitudinal movement of said knife blade, a correspondingly shaped metallic strip superimposed upon and integrally connected along one edge thereof with the forwardmost part of said tongue portion and said pointed portion to form a laminated point having two layers, one of said layers having a recess along the rearward edge of said point, and a flat slug of tungsten carbide rigidly secured in said last-mentioned recess to provide a cutting edge, said strip overlying only the forward part of said tongue portion and terminating at its rear in an edge providing a raised shoulder extending across said tongue portion and engaging the transverse forward face of said holder, thereby tending to prevent any rotation of said knife blade when secured within said holder during the use of the assembled knife.
